UNITED STATES PATENT OFFICE

JOHN N. NELSON, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND

SPECTACLE TEMPLE

Application filed March 20, 1928. Serial No. 263,047.

This invention relates to an improved construction of spectacle temples; and has for its object to construct such a temple with a wire core member covered with a non-metallic tube and to provide an enlargement on the end of the core where it projects beyond the tube to lock the tube on the core and to fit a cap member on the end of the tube to house the core enlargement and provide a finish for 10 the end of the tube.

With these and other objects in view, the invention consists of certain novel features of construction, as will be more fully described, and particularly pointed out in the appended 15 claims.

In the accompanying drawings:

Figure 1 is a side elevation showing a portion of a temple having a wire core covered with a non-metallic tube with a cap on the 20 end of the tube covering the enlargement of the wire.

Figure 2 is a short length of wire core showing one end enlarged.

Figure 3 is a short length of non-metallic 25 tubing designed to fit over the metallic wire core.

Figure 4 is a perspective view of a cap designed to fit onto the end of the tube and house the enlarged end of the wire core.

Figure 5 is a perspective view of a collar 30 or washer to rest against the end of the tube.

Figure 6 is a sectional end view of the core as extending beyond the end of the tubing and the cap fitted on the end of the tubing to 35 house the end of the core and the washer.

Figure 7 is a sectional end view on line 7—7 of Figure 6.

It is found in the construction and practical operation of spectacle temples of this character that where the wire core is covered with a non-metallic tube it is of advantage 40 to extend the core beyond the tube and enlarge its end to lock the tube on the core and in such cases it is found of advantage to provide a cap or cover for the projecting end of the core to protect this end from corrosion and make a finish for the end of the tube; and the following is a detailed description of the 45 present embodiment of my invention and

showing one construction by which these advantageous results may be accomplished:—

With reference to the drawings, 10 designates the wire core of a temple over which a non-metallic tubing 11 is passed, the ear-engaging loop portion 13 of the tubing being formed either plain or cut helically, as illustrated in Figures 1 and 3.

In order to secure the looped end of the tubing on its wire core, I preferably extend 60 the wire core beyond the end 14 of the tubing, as illustrated in Figure 6, and in some cases I preferably pass a metallic washer 15 over the end of the core to rest against the end 14 of the tubing and then flatten and so 65 enlarge or extend the end 16 of this wire core, which enlarged portion presses the washer against the end of the tube and locks the tube in place on the wire core.

As it would not be practical to leave the 70 metallic end of the core exposed, I have provided a simple and effective way for housing the same which is that of providing a cap 17 which has a bore 18 to fit over the 75 end of the tube, the bore being of a size to receive and house the washer 15 and also the enlarged end 16 of the wire core. In some instances, it is found of advantage to reduce the neck portion 19 of this cap member down to meet the surface of the tube as at 20, or 80 any other desired finish may be provided for this cap. In some instances, it is found of advantage to drill a vent hole 21 in the end of the cap to permit the escape of air when the cap is forced into position on the end of 85 the tube where it may be cemented in place.

This cap or end piece may be formed in any desired shape, in some cases it may be substantially the size of the tubing itself, while in still other cases it may be enlarged 90 beyond the diameter of the tube to form the desired finish on the end thereof.

My improved construction of temple is very simple and inexpensive to manufacture and will well serve the purpose of housing 95 the projecting metal parts covering them from sight and preventing corrosion of the same.

The foregoing description is directed solely 100 towards the construction illustrated, but

I desire it to be understood that I reserve the privilege of resorting to all the mechanical changes to which the device is susceptible, the invention being defined and limited only by the terms of the appended claims.

5 I claim:

- 10 1. A spectacle temple formed of a wire core covered with a non-metallic tube, means at the end of the tube for locking the tube to the wire, and an enlarged non-metallic cap having a bore to receive the end of the tube and the locking means to cover the same, the contacting surfaces of said end piece and tube being of non-metallic material and cemented together.
- 15 2. A spectacle temple formed of a wire core covered with a celluloid tube, means at the end of the tube for locking the tube to the wire, and an enlarged celluloid cap having a bore to receive the end of the tube and the locking means to cover the same, the contacting surfaces of said end piece and tube being of celluloid material and cemented together by softening the contacting surfaces.
- 20 25 3. In testimony whereof I affix my signature.

JOHN N. NELSON.
